UNITED STATES PATENT OFFICE.

LOUIS T. MATHEWS, OF HOUSTON, TEXAS.

COPYHOLDER AND INDICATOR FOR TYPING MACHINES.

Application filed August 3, 1925. Serial No. 47,659.

My invention relates to devices for indicating the point reached by the operator of a typing machine upon the copy which is being reproduced upon the said machine. It is adapted for use upon typewriters, linotypes and similar machines, where the operator has to reproduce, or copy, reading matter into printed characters.

It is an object of the invention to provide a copy holder, and a marker, movable thereon, so constructed as to indicate the position of the operator upon the copy at all times. It is desired that the marker be operated automatically by the carriage or some other moving part upon the type machine.

It is also an object to make the marker adjustable so as to accommodate it to follow lines in the copy of unequal length compared with the reproduction.

It is a further object that the device be capable of adjustment for different sizes of characters so that fine or coarse type may be followed. It is contemplated that the device be operated either automatically or by hand, as desired.

Further objects reside in the construction and arrangement of the parts which will more clearly appear from the more detailed description which follows.

Referring to the drawing herewith, Fig. 1 is a front elevation of a device embodying my invention. Fig. 2 is a rear elevation, some parts being broken away. Fig. 3 is a transverse section partly on the line 3-3 of Fig. 2, but showing the upper end of the supporting frame. Fig. 4 is a top plan view of the mechanism for manually operating the copyholder. Fig. 5 is a side elevation partly in section through the support and reel, illustrating the mechanism similar to Fig. 4. Fig. 6 is a top plan view partly in section of the automatic mechanism connected with the copy holder. Fig. 7 is a transverse section on the line 7-7 of Fig. 6. Figs. 8 and 9 are front and side elevations respectively of the line clamping mechanism. Fig. 10 is a top plan view of the operative connection for the pointer, which may be secured to the copy holder. Fig. 11 is a front elevation thereof. Like numerals of reference designate like parts in all the views.

A copy holder forming the principal portion of my invention includes a transverse

bar 1, which forms a supporting base for the device. Said bar 1 is supported at one end upon legs 2 rigidly secured to said bar and the opposite end is pivotally attached to a supporting leg 3. Said leg is formed with a laterally extending bracket 4 thereon, which fits between the two arms 5 of a bracket secured about the end of the base bar 1 by means of a pin 6. Said pin constitutes a pivot upon which the legs 3 may pivot, as will be later described.

Secured centrally of the bar 1 is an upright guide plate 7. Said plate is of the usual width of the copy which may be used on ordinary typing machines. It extends upwardly from the base, as shown particularly in dotted lines in Fig. 1, for a suitable distance sufficient to accommodate ordinary copy. It has its margins in-turned slightly, as shown at 8 in Fig. 10, thus forming one-half of a chamber 10.

A copy holder 9 is slidable vertically on the guide plate 7, and said copy holder comprises a plate similar in construction to the guide plate but adapted to fit around the forward face of said plate, as shown in Fig. 10, its side flanges 11 being clamped loosely about the guide plate so as to allow the copy holder to slide on said plate. The copy holder extends above the guide plate and has its upper end turned rearwardly to close the upper end of the chamber 10.

The guide plate 7 has secured thereto on its rearward side a plurality of supporting rods 12 and 13, as will be noted in Fig. 1. There is a pair of arms 12 and a similar pair 13. The upper rod 12 is secured rotatably within the plate 14 secured to the guide plate. It has a centrally extending arm 15 to which is secured a tension spring 16, extending downwardly toward the center of the plate, and attached to a bracket 17 on said plate. The said rod 12 has a curved portion 18 therein forming a sort of crank arm beyond which the rod is bent outwardly, then bent upwardly and forwardly, and is secured to a marker 19 by means of a clamp 20 on the rearward side of said marker. The rod 13 is also secured to the back of said guide plate by means of the clamping bracket 14. It is rotatable in this connection and has a crank arm 21 thereon, the rod being curved upwardly similar to the arm 12 and secured beneath the clamping bracket

105

20 below the arm 12. This construction will be readily understood by reference to Figs. 1 and 3.

The marker 19, which is held resiliently against the forward face of the copy holder by means of the arms 12 and 13, comprises a rule or straight edge, the upper edge of which forms a marker for the line of copy which is being reproduced. The outer ends

10 of the marker have thereon pulleys 23 which are rotatable upon pins 24, supported on their outer ends by a bracket 25 secured at the ends of the marker.

15 Two lateral supporting arms 26, one at each side of the copy holder, are secured to the back of the guide plate at a point approximately midway of the height of the plate. These arms may be made integral, if desired, approximately as shown in Fig.

20 10. The central portion between the two arms is secured adjustably to the plate by means of bolts 27 secured within one of a series of openings 28 in said plate. The arms extend forwardly from the rearward side of the plate and have the ends thereof recurved to form brackets 29 for the support of the pulleys 30. Said pulleys are mounted upon a cross pin 31 extending through the bracket thus formed and allowing the rotation between the two sides of the bracket of the pulleys 30.

25 A flexible cord or line 32 may be extended around the pulleys 30 and 23 at both sides of the holder, the lower portion 32 of which allows attachment thereof to the carriage, or other similar moving part of the typing device. The upper portion of the line, shown at 33, has secured thereon a pointer 34 which is adapted to move 30 with the line and has a point extending upwardly slightly beyond the edge of the marker 19.

35 The copy holder 9 is adapted to be moved vertically upon the guide plate by means of a line and reel. The line is secured at one end in an opening 35 in the lower end of the copy holder and is extended upwardly, between the two plates, within the chamber 10, to a pulley 36, which is mounted upon the guide plate within said chamber at the upper end of said plate. The line is then extended downwardly around a pulley 37 which is mounted upon the supporting frame 1 at the base. A pulley 38 is mounted in a vertical position upon the auxiliary supporting plate 39, secured to the bracket 4, previously described. The line which may be numbered 40 is extended about this pulley and forwardly along the 40 support 39 for engagement about a drum or reel 41.

45 The auxiliary supporting plate 39 extends forwardly from the bracket 4, preferably at the right of the operator, to a point spaced conveniently within reach. It has a for-

ward supporting leg 42, and its opposite sides have upwardly extending plates or flanges 43, which form a support for the transverse shaft 44 upon which the reel 41 is rotatable. It will be noted that the body 70 of the supporting base is U-shaped and has, in effect, a channel iron construction.

50 Between the two side plates 43 the reel 41 is journaled. The shaft 44, upon which the reel is fixed, rotates in the said plates 75 and has, on opposite sides thereof, ratchet wheels 45. The line 40 is wound about said reel and secured thereto as shown at 46.

55 The reel is rotatable to wind up the line 40 thereon by means of a pawl 47 formed upon a bell crank lever pivoted at 48 and having its upper arm formed into a handle 49 by means of which the pawl may be operated. The said pawl is pivoted upon a lever arm 50 which is curved downwardly 60 at its forward end and pivoted to a cross pin 51 between the two side plates 43. It has a downwardly extending lug 52 thereon in which the pin 48 is pivotally supported. The forward end of the lever 50 65 is extended within the reach of the operator and forms a handle 53 by means of which the pawl 47 may be depressed. The said pawl 47 is held in engagement with the teeth of the ratchet wheels 45 by means 70 of a spring 54 secured at 55 to the forward end of the lever 50. The lever 50 is in turn held in a raised position by means of a spring 56 secured to said lever at 55 and to the plate 43 at 57.

75 A second pawl 58 is pivoted at 59' to the side plates 43, its lower end being curved inwardly toward the ratchet wheels 45 and adapted to engage the teeth thereof. It is held in engagement with the teeth of the 105 ratchet wheel by means of a spring 59 secured to the upper arm 60 of the pawl and at its opposite end to a pin 61 in one of the side plates 43. It will be noted that the pawl 47 is directly above and in front 110 of the pawl 58 so that when the arm 49 of the forward pawl is depressed, it will throw the pawl 47 out of engagement with the ratchet wheel, bringing the same into contact with the pawl 58, and serving to 115 disengage said pawl 58 also from contact with the ratchet wheel, thus releasing the reel so that the line may unwind, when the force of gravity causes the copy holder to fall. A curved spring 62 is secured at 63 120 upon the base plate and extended around the forward end of the ratchet wheels, serving to protect the forward side thereof and acting slightly as a brake to prevent too rapid rotation thereof.

125 A lateral arm 63 is formed upon the shaft 44 having a thumb nut 64 thereon whereby the rotation of the shaft 44 may be readily accomplished. The upward movement of the lever 50 through the action of the spring 130

56 is limited by an arm 65 formed upon a bracket 66 adjustably secured at 67 to the side plate 43, as shown in the drawing. The thumb nut 68 extending through a slot in 5 said bracket allows the arm 65 to be set at any desired height relative to the said lever 50.

The auxiliary base plate 39 may be swung on the pivot formed by the pin 6 into a 10 position parallel with the base plate 1. It is adapted to be held in position extending forwardly from said plate by means of a hooked latch 69 pivoted at 70 upon the plate 1 and engaging at its forward end about an arm 15 72 extending rearwardly from the auxiliary plate 39, as shown best in Fig. 4. This allows the auxiliary base plate to be swung out of position when the device is not in use, in an obvious manner.

20 It is desired that the marker and the pointer both be operated automatically, when desired, by the movement of some part of the typing machine. When the device is to be operated by the carriage of the typewriter, 25 as will be most commonly the case, I have devised the mechanism shown in the drawing for accomplishing this purpose. To move the pointer 34 a bracket 73, shown in Figs. 1, 8 and 9, is secured to the rearward frame 30 of the carriage shown fragmentarily at 74. Said bracket has thereon an upwardly extending plate 75 which is bent forwardly to form a hooked end 76, best shown in Fig. 9. On the forward side of the plate 75 is pivoted 35 a dog 77 which has its upper end curved forwardly and hooked at 78 directly beneath and within the hooked end 76 of the plate. A space 79 is thus formed between the plate and the dog, which is adapted to receive the 40 line 32 of the pointer. When the dog 77 is swung upwardly on its pivot, it is adapted to clamp the line within the space 79 and hold it firmly in engagement with the typewriter carriage. This clamping engagement 45 is accomplished by means of a latch pivoted on the plate 75 at 80 and having an upwardly extending arm 81^a curved on its upper end to form a cam to engage beneath the lower hooked end of the dog and force it 50 into clamping position. The dog 77 has a short arm 82^a extending forwardly on its lower side to be engaged by the arm 81^a when the arm is swung out of clamping engagement with the dog. Thus when the upper arm 81^a of the latch is moved to the 55 right, it will release the dog and the arm 81^a will engage the arm 82^a upon the dog and throw it downwardly away from the hooked end 76 of the clamp. It will be noted that 60 the engagement and disengagement, of the clamping device thus formed, relative to the line 32 may be quickly and easily made so that the line 32 may be adjusted in position relative to the clamp without material loss 65 of time.

To move the copy holder 9 automatically relative to the lines of the copy, I have provided a reel 81 which is supported upon a rod 82 extending forwardly from the left-hand side of the base plate 1. Said reel is 70 mounted upon a rod or shaft 83 secured at one end within the base plate 1 and at its outer end within the up-turned end 84^a of the rod 82. The said reel is positioned on the rod 83 at a point closely adjacent the base 75 plate 1. It has secured thereon a line 84 which is extended along the base plate and secured about a pulley 85 spaced somewhat from the center of the plate 1, and from thence it is extended upwardly about a pulley 86 in the upper end of the guide plate, and from thence to the point 35' where it is secured to the copy holder. It will, therefore, be noted that the rotation of the reel 81 will act to raise the copy holder upon the 85 guide plate in the same manner as is done through the line 40, previously described.

The shaft 83, upon which the reel 81 is mounted, may be rotated through the operation of the carriage by means of a lever 86 90 secured on said shaft at a point even with the carriage of the typewriter. The lever 86 is rotatable on the shaft 83. It has its upper end perforated at 87 to provide means for connecting the same with the carriage 95 of the typewriter. Its lower end is extended beyond the shaft 83 and has pivoted thereon a dog or pawl 88.

Immediately adjacent the lever 86 is a ratchet wheel 89 fixed to the shaft 83 and 100 rotatable therewith. The dog 88 upon the lever 86 is held resiliently against said ratchet wheel to engage the teeth thereof by means of a spring 90. There is also a pawl 91 secured adjacent the latch wheel upon an 105 arm 92 and adapted to press firmly against the teeth of the ratchet wheel 89 through its own resiliency.

Mounted in the up-turned end 84^a of the base 82 at one end and upon the base 1 at 110 its other end is a rod or shaft 93. Said shaft has on its forward end a crank arm 96 by which it may be rotated. Adjacent the lever 86 there is fixed on said shaft a downwardly inclined arm 97 which presses 115 against the rearward side of the pawl 88 and against the forward end of the pawl 91. It will thus be seen that by rotating the shaft 93 through the crank arm 96 the arm 97 may be thrown against the dogs 88 and 91, forcing them out of engagement with the ratchet wheel in an obvious manner. The lever 86 is held resiliently toward the arm 92 by means of a spring 94 so as to normally throw the lower end and the pawl 88 backwardly when it has been advanced by the movement of the typewriter carriage.

When the copy holder has been raised to its highest point and it is desired to drop the same, this may be done by the mecha-

nism just described, releasing the ratchet wheel and the reel whereby the weight of the copy holder will cause it to drop unreeling the line from the drum. This sudden drop of the copy holder is counter-balanced to some extent and thus slowed up by the use of a weight which may be placed in the line, as shown at 98 in Fig. 1. It will be noted that a weight 98 may be placed in either of the lines 40 or 84, as indicated in dotted lines in Fig. 1. A holding rod 100 may be employed to assist in holding the copy against the holder. This holding rod may have a plurality of friction sleeves 101 thereon to bear against the copy on the forward side of the holder. The rod 100 is extended beyond the sides of the holder and then bent downwardly and rearwardly and through the side wall of the holder 9, and across the back of said holder and the end up-turned at 102 engages beneath the curved wall of the holder. The opposite end of the rod is similarly extended across the rearward side of the holder and secured beneath the opposite side thereof. Intermediate rings 103 may be employed to secure the rods together, as shown in the drawing. This holding rod is simple and efficient in its action, and the resiliency of the rod itself serves to hold the friction members 101 resiliently pressed against the forward face of the holder.

In order to adapt the use of the pointer 34 to different sizes of type, it is necessary to move the pointer by steps of varying length with the operation of the keyboard. This may be done by the modification of the pulley 30, shown in Fig. 1 and previously described, and also including the use of a separate connecting line therewith. In Figs. 10 and 11, this modified form of structure is shown. At one end of the frame 26' upon which the lower pulleys are mounted, I curve the end at 30' to form a wider spaced support for the pulley shaft or pin 104 at one end of the frame and the pin 105 at the opposite end thereof. A pin 104 serves to support a compound pulley having several stages, of which I have shown 3 indicated at 106. The compound pulley 106 is formed with three drums of varying sizes, the middle one of which is shown as receiving the line 32, described in the previous embodiment. At the opposite end the line 32 engages about a smaller pulley 107 mounted upon the pin 105. A second pulley 108 is mounted upon the same pin 105 and spaced from the pulley 107 by the plate 109. A second line or cord 110 is secured about the pulley 108 at one end and then about the larger drum upon the pulley 106. It is preferably wound twice around the drum of the pulley 106 so that its movement will cause the rotation of said pulley, and thus serving to reel up or unreel

the line 32, also engaging about the said pulley. This device is connected to the clamping bracket 73 upon the typewriter carriage by engaging the same upon the cord or line 110. The movement of the carriage will then cause the movement of the said line 110, causing rotation of the pulley 106. This will cause the reeling up of the line 32 connected with the pointer. It will thus be seen that the movement of the pointer will be slowed down somewhat by this connection. If it is desired to speed up the movement of the pointer, as when larger type is to be copied, the cord 110 may be engaged about the smaller drum on the pulley 105 so that its movement will increase the speed of the movement of the cord 32, to which the pointer is attached. The arrangement will be seen to be a simple device for increasing or decreasing the speed of movement of the cord 32 and the pointer 34 attached thereto.

It is to be understood that while I have shown the larger pulley 106 at the right of the operator, the position of these pulleys may be reversed without departing from the spirit of the invention. It is also to be noted that the position of the actuating means for the copy holder may be changed without materially altering the invention. The reel 81 may be placed at the right of the machine, if desired, or the reel 41 at the left. The positioning of these actuating devices relative to the copy holder is one of convenience only and may be changed without in any way departing from the spirit of the invention.

A spring controlled arm 115 is provided for holding the pages of the copybook out of the way during the operation of the device. This arm has a curved length of wire pivoted at 116 to the rearward side of the holder. There is an arm 117 extending diagonally downward away from the pivot to which a spring 118 is attached, said spring being secured at its opposite end to the frame of the holder and thus tending to draw the arm 117 to the right of its position, as shown in Fig. 2. The upper arm of the attachment is extended to one side and then curved upwardly and downwardly to contact with the upper rim of the holder. A clamping member 119 is formed to lie along the upper edge of the holder, said clamping member being held resiliently against the holder by means of the spring 118, as will be obvious from Fig. 1.

It is believed that the operation of the device has been made clear. The copy which is to be reproduced will be secured behind the holding rod 100 and the marker 19 will be held resiliently against the copy so as to indicate the line which is being copied. When the device is operated by hand, the line 84 will be unreeled and will have no effect whatever upon the movement of the

copy holder. The operating lever 50 and its connected pawls will serve as a means to reel up the line 40 upon the drum 41 and raise the copy holder one space relative to the marker 19 at each time the lever 50 is depressed. The manner in which the copy holder is raised will be easily understood from the drawing.

As the carriage of the typewriter is moved

- 10 to the left during the typing of a line, the clamp upon the plate 75 will engage the line 32 and cause the pointer 34 to be moved simultaneously with the carriage and at the same rate so that the pointer will at each
- 15 movement show the character which is to be reproduced. If the words upon the copy will not always coincide with the number of words which may be printed upon the page which is being written, thereby making it
- 20 necessary to carry one, or more, word over from one line to the next, the pointer may be adjusted at the end of the line by releasing the cord within the space 79 of the clamp and moving the pointer to indicate
- 25 the desired word to be written at the beginning of the following line, and when the word has been reproduced and the matter written, the pointer may be again moved to the beginning of the subsequent line, and the
- 30 clamp on the plate 73 may be again secured to the line causing the pointer to be moved with the operation of the carriage. The use of the compound pulley disclosed in Figs. 10 and 11 has already been described and
- 35 may be available for use where small or unusually large type are to be copied.

When the copy holder is to be moved automatically with the operation of the carriage, as may be sometimes done where the lines

- 40 and characters are the same size on the copy as in the typewritten matter, the carriage will be connected at one end to the lever 86 by any desired means. The movement of the carriage to the right when a new line of
- 45 matter is to be typed will cause the reel 81 to be rotated to wind up the cord 84 and the length of the lever 86 will be such that the movement of the carriage through the usual distance will reel up the cord 84 a sufficient
- 50 amount to lift the copy holder through the distance of one line. The length of the lever 86 may be varied by connecting the carriage thereto through any one of the series of openings 87 in said lever.

- 55 When a page of a copy has been typed and a new page is started, the copy holder 9 will be dropped to its lowest point in the position shown in Fig. 1. This is accomplished by the use of the automatic device
- 60 just described by moving the crank arm 96 on the shaft 83 so as to throw the arm 97 on said shaft to the left of the position shown in Fig. 1 so as to release the pawls 88 and 91 and allow the weight of the copy holder to drop, unreeling the line 84 from

the reel. The speed of the dropping copy holder will be regulated by the weight 98, as previously set forth.

In releasing the copy holder in the hand-operated device controlling the reel 41, the arm 49 of the pawl 47 may be depressed to release both the pawls 47 and 58, thus allowing the copy holder to drop in the same manner as previously described.

It is of advantage when the device thus described is to be stored to fold the device into compact shape and this is assisted by the pivotal connection between the supporting base 39 and the latch 69 by means of which it is held in open position, as described. The further objects and advantages of the invention will be apparent to those skilled in the art, and while I have illustrated certain details of construction, it is to be understood that these details are illustrative of one embodiment only of the invention, and that various changes may be made therein for adapting for attachment to different forms of typing machines coming within the scope of the invention, and I do not wish to be confined to the specific details herein set forth and described.

What I claim as new and desire to protect by Letters Patent is:

1. In combination with a typing machine having moving parts thereon, a copy holder adjacent thereto, a line marker extending horizontally across the front thereof, means to adjust said holder vertically relative to said marker, a pulley at each end of said marker, a pair of lateral supporting arms extending from each side of said holder, pulleys at the ends of said arms, a flexible line extending around all of said pulleys and across the face of said marker, a pointer on said line, and means to move said line and said pointer along said marker actuated by the said moving parts.

2. In combination with a typing machine having a keyboard and a carriage movable through the operation of said keyboard, a copy holder adjacent said carriage, a line marker extending across said holder, means to adjust said holder vertically relative to said marker, pulleys at each end of said marker, laterally extending arms on each side of said holder below said marker, pulleys at the ends of said arms, a flexible line extending around said pulleys, a pointer on said line adjacent the edge of said marker, and means on said carriage engaging said line to move it when said carriage is moved.

3. In a device of the character described, a keyboard, a member moved laterally through the operation of said keyboard, a copy holder, a line marker relative to which said holder is vertically movable, a flexible line supported for movement along said marker, a pointer on said line, and means on said member detachably engaging said

- line to move said line and said pointer along said marker, said means comprising a hooked plate, a clamping dog pivoted thereon, and a cam latch to move said clamping dog 5 against said plate.
4. In a device of the character described, a keyboard, a member moved laterally through the operation of said keyboard, a copy holder, a line marker on said copy holder, a flexible line supported for movement along said marker, a pointer on said line, and means on said movable member to move said line and said pointer along said marker, said means comprising a hooked 10 plate, a clamping dog pivoted to said plate, a latch pivoted on said plate below said dog, a curved upper end on said latch engaging said dog whereby said dog may be forced into clamping engagement with 15 said plate.
5. In a device of the character described, a supporting base, an upright guide plate on said base, a copy holder slideable vertically on said guide plate, pulleys on said plate, a flexible line passing over said pulleys and secured to said copy holder, a reel spaced forwardly from said plate, a ratchet wheel on said reel, a pawl held resiliently in engagement with said ratchet, means to rotate 20 said reel, and means to disconnect said rotating means and said pawl from said ratchet, said line being connected with said reel for moving said copy holder.
6. In a device of the character described, a supporting base, an upright guide plate thereon, a copy holder slideable vertically on said guide plate, a pulley at the upper end of said guide plate, a flexible line secured to the lower end of said copy holder and 25 passing over said pulley, a reel spaced forwardly from said plate, said line being connected with said reel and adapted to be wound thereon to raise said copy holder, and means to rotate said reel, comprising a ratchet on said reel, a lever, a spring pressed pawl thereon, a second pawl engaging said ratchet, said spring-pressed pawl having an arm thereon whereby it may be depressed to release both said pawls from said ratchet 30 for the purpose described.
7. In a device of the character described, a guide plate, a copy holder slideable vertically on said guide plate, a flexible line connected with the lower end of said copy holder and adapted to raise said copy holder, a reel upon which said line is adapted to be wound, a ratchet on said reel, a lever pivoted adjacent said reel, a pawl on said lever, a second pawl engaging said ratchet below 35
- said first mentioned pawl, and an arm on 60 said first mentioned pawl whereby both said pawls may be released from said ratchet.
8. In combination with a typing machine having a keyboard and a carriage movable through the operation of said keyboard, a copy holder adjacent said carriage, a guide plate upon which said copy holder is slideable, a flexible line secured to the lower end of said copy holder, a reel spaced forwardly from said guide plate, said line being connected with said reel to raise said copy holder, and means to rotate said reel comprising a ratchet wheel thereon, a lever secured on the axis of said reel, a ratchet wheel on said reel, a pawl engaging said ratchet and adapted to prevent rotation thereof in one direction, a second pawl on said lever engaging said ratchet, said second pawl being arranged to release said first mentioned pawl when desired. 70
9. In a device of the character described, a supporting base, a guide plate thereon, a copy holder slideable vertically on said guide plate, automatic means to raise said copy holder relative to said plate, a retaining arm pivoted on the upper end of said copy holder said arm being curved to rest on the upper end of said copy holder and a spring acting to hold said arm resiliently against said holder. 80
10. In a device of the character described, a supporting base, a guide plate thereon, a copy holder slideable vertically on said guide plate, a line marker secured on said plate and extending across the forward face of said copy holder, a plurality of resilient arms secured to the rearward side of said marker, a pivotal attachment for said arms with said plate, and resilient means connecting with said arms to hold said marker 90 against said copy holder. 95
11. In combination with a typing machine having a keyboard and a carriage movable through the operation of said keyboard, a copy holder adjacent said carriage, a line-marker adjacent said holder, means to adjust said holder vertically relative to said marker, pulleys at each end of said marker, a flexible line extending around said pulleys and forming a closed circuit, and means to 105 connect said line to said carriage at any desired position of said carriage, a pointer on said line adjacent the edge of said marker, said line and pointer being movable simultaneously with said carriage. 110
- In testimony whereof I hereunto affix my signature this 29th day of July, A. D. 1925
- LOUIS T. MATHEWS. 115
